Primary Examiner—A. Hugo Word*Assistant Examiner*—Celia A. Murphy*Attorney, Agent, or Firm*—Michael Sand Co.[57] **CLAIM**

The ornamental design for a security holder for a compact disc, as shown and described.

DESCRIPTION

FIG. 1 is a perspective view of a security holder for a compact disc showing our new design in a partially open condition;

FIG. 2 is a reduced top plan view thereof, the lid shown fully open;

FIG. 3 is a bottom plan view of FIG. 2;

FIG. 4 is a left side elevational view of FIG. 2;

FIG. 5 is a right side elevational view of FIG. 2;

FIG. 6 is a front elevational view of FIG. 2, the rear being a mirror image;

FIG. 7 is a top plan view of FIG. 7, the lid shown closed;

FIG. 8 is a bottom plan view of FIG. 7;

FIG. 9 is a left side elevational view of FIG. 7;

FIG. 10 is a right side elevational view of FIG. 7; and,

FIG. 11 is a front elevational view of FIG. 7, the rear being a mirror image.
